[57] CLAIM

The ornamental design for a hand held computer, as shown and described.

DESCRIPTION

FIG. 1 is a front, top and right side perspective view of a hand held computer showing our design;

FIG. 2 is a front elevational view thereof;

FIG. 3 is a top plan view thereof;

FIG. 4 is a left side elevational view thereof;

FIG. 5 is a right side elevational view thereof;

FIG. 6 is a rear elevational view thereof;

FIG. 7 is a bottom plan view thereof; and

FIG. 8 is a front, top, and right side perspective view thereof, with the cover pivoted to the open position for access to the keyboard and display.

*FIG. 1**FIG. 2**FIG. 3*FIG. 4

FIG. 5

FIG. 6

FIG. 7

FIG. 8
